Primary Examiner — Garth Rademaker*Assistant Examiner* — Angel R Marrero-Arce(74) *Attorney, Agent, or Firm* — Thomas P. O'Connell; O'Connell Law Firm(57) **CLAIM**

The ornamental design for a digital audio player as shown and described.

DESCRIPTION

FIG. 1 is a perspective view of a digital audio player showing my new design.

FIG. 2 is a left side elevation view thereof;

FIG. 3 is a right side elevation view thereof;

FIG. 4 is a rear elevation view thereof;

FIG. 5 is a front elevation view thereof;

FIG. 6 is a top plan view thereof; and,

FIG. 7 is a bottom plan view thereof.

The dashed broken lines depict portions of the digital audio player that form no part of the claim.

1 Claim, 7 Drawing Sheets
